UNITED STATES PATENT OFFICE.

FREDERICK W. SIEVERS, OF BROOKLYN, NEW YORK.

LIFE-BOAT HOLDING AND LAUNCHING DEVICE.

1,248,183.

Specification of Letters Patent. Patented Nov. 27, 1917.

Application filed March 14, 1917. Serial No. 154,693.

To all whom it may concern:

Be it known that I, FREDERICK W. SIEVERS, a citizen of the United States, and a resident of the city of New York, borough of Brooklyn, in the county of Kings and State of New York, have invented a new and Improved Life-Boat Holding and Launching Device, of which the following is a full, clear, and exact description.

10 This invention relates to life-boat holding and launching devices, and the invention has for its general objects to provide a device of this character which is of comparatively simple and inexpensive construction, 15 reliable and efficient in use and so designed that the life-boat can be launched with a maximum despatch and a minimum effort.

20 A more specific object of the invention is the provision of a simple, novel and effective means for releasably holding the life-boat on its truck in such a manner that the boat is normally rigidly supported but which can be readily unlocked and released from the truck.

25 With such objects in view, and others which will appear as the description proceeds, the invention comprises various novel features of construction and arrangement of parts which will be set forth with particularity in the following description and claims appended hereto.

30 In the accompanying drawing, which illustrates one embodiment of the invention and wherein similar characters of reference indicate corresponding parts in all the views,

Figure 1 is a side view of the device with a portion in section;

Fig. 2 is an end view; and

40 Fig. 3 is a detail sectional view showing one of the keel supporting blocks and its holding means.

45 Referring to the drawings, A designates a life-boat, B the davits and C the block and tackle by which the life-boat can be raised or lowered from the davits.

50 On the deck 1 are the rails 2 on which travels a truck D. This truck is provided with wheels 3 which ride on the rails, and on two or more corners of the truck body are clamps 4 which grip the rails 2, the clamps being fastened by means of a crank nut 5 threaded on a screw 6 which is fastened to one of each set of jaws and passes 55 through the other jaw. By loosening the

nut the jaws are released from the rails so that the truck can be moved.

The boat A is normally supported on blocks 7 which lie under the keel 8 and directly support the same. These blocks are 60 pointed or V-shaped at their lower ends 9 and seat in recesses 9^a in the top surface of the truck, and consequently the supporting blocks are unstable, so that they will immediately drop out of the way when their 65 holding means is released. Each block is held by a clip or yoke 10 which is fixed on an arm 11 carried on a horizontal rock shaft 12, which shaft is journaled in bearings 13 fastened to the sides of the truck. On the 70 outer ends of each shaft 12 are arms 14 whereby the shafts 12 can be rocked to engage the holding clips 10 with or disengage them from the blocks 7. The arms 14 are held in locking position by any suitable 75 means, such as a ring 15 engageable over each arm when the latter is in an upright position. The rings are slidable on links 16 on the lower ends of the bracing chains or elements 17, which latter have their links 16 80 fastened to the body of the truck, and the upper ends of the elements 17 are engaged by releasable catches 18 with gunwale gripping hooks 19.

When it is desired to launch the boat the 85 rail clamps 4 are released so that the truck can be shifted into close proximity to the edge of the deck of the ship, and these rings 15 are raised to disengage the arms 14 so that the latter can be thrown outwardly 90 from the full to the dotted-line position, Fig. 1, thereby releasing the blocks 7 so that they will drop from engagement with the boat. The bracing elements 17 are next detached so that the boat can swing outwardly 95 on its davits free from the truck and be launched.

To hold the keel of the boat normally fixed the arms 11 have recesses 20 at their upper ends so as to receive the keel and 100 thereby hold the life-boat against lateral displacement on the supporting blocks 7. The blocks 7 are permanently fastened to the truck by means of ropes 21 or equivalent means fastened to the blocks and to the 105 truck, as clearly shown in Fig. 1.

The clamps 4 are especially useful to control the travel of the truck in case the boat or vessel lists to one side. The clamps are loosened just sufficiently to allow the truck 110

to slide slowly down the rails, or, in other words the clamps can frictionally grip the rails with a grip which can be regulated, and consequently the launching of the life boat can be more reliably effected.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters Patent:

1. The combination of a truck, a life-boat, unstable blocks having pointed lower ends resting on the truck and on which the keel of the life-boat rests, and means for releasably holding the blocks in boat-supporting position.

2. The combination of a truck, a life-boat, unstable blocks having pointed lower ends resting on the truck and on which the keel of the life-boat rests, and elements movably mounted on the truck to releasably hold the blocks normally stationary.

3. The combination of a truck, a life-boat, unstable blocks resting on the truck and on which the keel of the life-boat rests, and elements movably mounted on the truck to releasably hold the blocks normally stationary, said elements having means for releasably engaging the keel of the boat to prevent lateral movement of the keel on the said blocks.

4. The combination of a truck, a life-boat,

supporting blocks having pointed lower ends resting on the truck and on the top surfaces of which the keel of the boat rests, rock shafts on the truck, arms on the shafts, yokes on the arms for normally holding the blocks upright, and means for releasably holding the shafts with the yokes engaged with the blocks.

5. The combination of a truck, a life-boat, supporting blocks having pointed lower ends resting on the truck and on the top surfaces of which the keel of the boat rests, rock shafts on the truck, arms on the shafts, yokes on the arms for normally holding the blocks upright, and means for releasably holding the shafts with the yokes engaged with the blocks, said arms having recesses to engage the keel of a boat when the arms are upright.

6. The combination of a truck, a life-boat, supporting blocks having pointed lower ends resting on the truck and on the top surfaces of which the keel of the boat rests, rock shafts on the truck, arms on the shafts, yokes on the arms for normally holding the blocks upright, means for releasably holding the shafts with the yokes engaged with the blocks, said arms having recesses to engage the keel of a boat when the arms are upright, and releasable bracing elements between the gunwales of the life-boat and the truck.

7. The combination of a truck, unstable blocks on the truck, a life-boat having its keel normally resting on the blocks, swinging devices mounted on the truck to releasably hold the blocks in normal position, arms on the devices, braces between the life-boat and truck, and means on the braces for engaging the arms to hold the devices engaged with the blocks.

FREDERICK W. SIEVERS.
